UNITED STATES PATENT OFFICE.

HARVEY P. BOSTAPH, OF DETROIT, MICHIGAN.

RETOURT.

1,204,646.

Specification of Letters Patent. Patented Nov. 14, 1916.

Application filed January 19, 1916. Serial No. 73,011. Renewed September 16, 1916. Serial No. 120,582.

To all whom it may concern:

Be it known that I, HARVEY P. BOSTAPH, a citizen of the United States, residing at Detroit, in the county of Wayne and State of Michigan, have invented a new and useful Retort, of which the following is a specification.

This invention has reference to retorts for the destructive distillation of coal, and its object is to provide a retort for such purpose whereby the coal is converted into coke capable of burning with a long smokeless flame, and whereby the volatile matter driven off during the coking operation and recoverable is of increased quantity and of superior quality.

In accordance with the present invention the retort is so constructed as to contain the coal to be treated in relatively narrow columns, so arranged that heat applied to the exterior of the retort acts on each column of coal along one long edge and progressively toward the other long edge, with the gases of distillation escaping from the column of coal along the long edge remote from that to which the heat is initially applied, such escape being facilitated by the production of subatmospheric conditions.

For commercial reasons the retort is so constructed as to include a series of thin columns of coal grouped about a central duct into which the gases of distillation pass, and from which they are withdrawn, while the columns are separated by division walls extending from the central duct to the outer shell of the retort, thus providing heat conducting means of greater permeability to heat than the columns of coal.

The retort is customarily made of columnar form with a central longitudinal duct and radial division walls extending therefrom to the shell of the retort, whereby the coal columns are of segmental cross-section of greater radial depth than circumferential width, and each column communicates with the central duct along the inner long edge.

The retort has the central duct and all or some of the webs constituting a removable core for the shell of the retort, whereby the core may be lowered from the retort in order to discharge the coke and at the same time

sufficiently chill the core that when again introduced into the retort and the latter is charged with coal, the temperature to which the coal is initially subjected is considerably lower than the temperature to which the retort is constantly subjected, so that the coal is treated progressively by heat conducted from the outer edges of the coal columns toward the inner edges thereof, because of the heat conductivity of the division walls. The separate core facilitates the discharge of the coked contents of the retort, this discharge being further facilitated by initial cooling due to the introduction of steam into the retort.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—Figure 1 is a longitudinal vertical section of a retort embodying the present invention. Fig. 2 is an elevation partially in section showing the bottom end of the retort and the core lowered therefrom, as well as some portions of the core lowering and lifting means. Fig. 3 is a cross-section of the core on the line 3—3 of Fig. 1. Fig. 4 is a cross-section of a fragment of the retort shell and core showing a slight modification.

Referring to the drawings there is shown a shell 1 of columnar form, which in the installed position is upright, and this shell tapers from the bottom toward the top and is free from interior obstruction. The upper and lower ends of the shell are provided with closures in the form of heads 2 and 3, respectively. The head 2 has a circumferential groove on its under face at its peripheral portion to receive a packing gasket bearing against the upper edge of the shell 1, whereby the retort may be hermetically closed by the head 2. To hold the head

- in place it is provided with outstanding lugs 5 and the body or shell 1 of the retort has ears 6 thereon carrying eye bolts 7 adapted to the lugs 5, whereby the head 2, 5 while readily removable from the retort, may be tightly clamped thereagainst. A central eye 8 constitutes a convenient means for lifting the head 2 from the retort shell or body 1 when it is desired.
- 10 Surrounding the shell is an inclosing wall 9 which may be made of fire brick of any suitable form, the inner wall of the fire-brick envelop being in spaced relation to the outer wall of the retort shell, such spacing being sufficient to insure an even distribution of heat applied to the outer wall of the envelop 9 and transmitted through the fire brick to the retort.
- The lower head 8 has a marginal flange 20 10 constituting a ledge carrying a packing gasket 11 bearing against the lower end of the shell 1, being held tightly thereto by eye bolts 12 engaging lugs 13 projecting from the flange 10 and carried by ears 14 25 on the lower end of the shell when in projecting relation to the outer wall thereof. The ears 14 form part of brackets 15 on the retort shell engaging channel beams 16 forming part of the framework of the 30 installation. The beams 16 carry a floor 17 upon which is supported the fire-brick wall or envelop 9. A commercial installation includes as many retorts as may be desired, so that the channel beams 16 and the floor 35 17 may be considered as but parts of an installation including a battery of retorts and including means for the application of heat to the exterior of the envelop 9.
- On that surface of the head 3 which in 40 45 the installed position constitutes the upper face thereof, there is formed a central socket 18 and surrounding sockets 19, which latter may be provided with set screws 20. The sockets 19 receive upright rods 21 which may be held thereto in any desired position by the set screws 20. At the upper ends 50 55 the rods 21 enter other sockets 22 formed on the under face of a frusto-conical bottom plate 23 forming part of a core 24 adapted to the shell 1 for a purpose which will presently appear. Each socket 22 is provided with a set screw 25, so that by means of the set screws 20 and 25 and the rods 21 the core may be spaced from the head 3 to form a chamber 26.
- Rising centrally from the plate 23 is a 60 65 tubular duct 27 extending to a height somewhat short of the top of the shell 1 and there carrying a distributing hood 28 having side openings 29 through it.
- Radiating from the tubular duct 27 are webs 30 arranged in circular series, and in the particular construction shown in Figs. 1, 2 and 3 the webs are all carried by the core. Between the webs the wall of the duct 27 has perforations 31 therethrough. The webs extend in radial relation to the duct 27 into close relation at their outer edges to the inner wall of the shell 1, but clearance is provided to allow for expansion 70 of the parts when the retort is heated, the plate 23 also being of a diameter to allow some clearance. It is feasible to have some of the webs, say, the alternate ones, project inwardly from the shell. Such alternate 75 arrangement of the webs is shown in Fig. 4, illustrating a small portion of the core with outwardly projecting webs 30 alternating with other like webs 30^a projecting inwardly from the shell 1.
- The socket 18 receives the lower end of a rod 32, having at the upper end a baffle plate 33 entering the lower end of the duct 27, the purpose of this plate being to prevent radiation of heat into the chamber 26 80 to any harmful extent.
- At the upper end of the retort is an outlet pipe 34 for conducting away the gases of distillation and through which subatmospheric conditions may be established and 85 maintained during the coking operation. Near the bottom of the retort in position to enter the chamber 26 is another pipe 35 by means of which steam may be introduced into the chamber 26 for a purpose which 90 will hereinafter appear.
- In the use of the retort the core 24 is removed and replaced from time to time, and one means for accomplishing this purpose is illustrated in Figs. 1 and 2. There is provided a frame 36 in which there is mounted a carrier 37 supported by ropes or cables 38 passed over pulleys 39 and carrying counterweights 40. The carrier 37 has thereon a post 41 in position to enter a socket 42 100 105 formed on the under side of the head 3. The counterweights are sufficient to overbalance the core 24 and hold it within the retort when the retort contains no charge, but the core with a charge therein is of sufficient 110 weight to overbalance the counterweights 40. With the core lodged within the retort shell 1 and the head 3 clamped in place, but with the head 2 removed, the retort is ready to be charged with the coal to be coked. There 115 are other carbonaceous materials besides the substance known as coal which may be coked, but for the sake of simplicity of description coal only will be referred to with the understanding that the word is intended to cover 120 any other material suitable for the purpose. The coal is introduced through the then open upper end of the retort and falling upon the hood 28, which protects the duct 27 from access of the coal, is distributed into 125 the various tubes or chambers indicated at 43 and defined between the webs 30, the duct 27 and the shell 1, the plate 23 forming an outwardly declining bottom closure for the coal tubes or chambers. After the coal tubes 130

have been filled with coal, the cover 2 is secured in place and subatmospheric conditions are established through the pipe 34. Heat applied to the exterior of the retort 5 first affects the coal columns within the tubes or chambers 43 at their outer long edges and progressively toward the duct 27. The heat is conducted by the webs 30 from the exterior of the retort toward the center thereof 10 of, these webs presenting better heat conductors than the coal. The result is that distillation and coking begins at the outer long edge of each column and continues toward the inner long edge without requiring 15 that the periphery be treated to an objectionable temperature, as would be the case were heat to distil the center of the mass conducted through the coked peripheral portions. Since the gases are being continually 20 withdrawn there is no chance of enveloping the deeper portions of each column of coal in coked material, whereby the escape of gases would be hampered and a high temperature be necessary to effect the complete 25 coking of the material. Instead, the action of the heat from one edge of each coal column to the opposite edge proceeds progressively and finally produces a uniform coking throughout the column, so that the coking 30 is completed within a commercially reasonable time and beneficial results are obtained which will be apparent to those skilled in the art.

Because of the construction of the retort 35 and the production of subatmospheric pressure within the retort during the coking operation, the whole operation is performed at a comparatively low heat not exceeding about 1100° F., the process beginning at 40 about 700° F. with the heat increasing progressively through the column of coal up to the higher temperature, which usually is from 1000° to 1100° F., although for some coals it may be as low as 900° F.

45 The coking operation may be carried on continuously with the maximum heat employed maintained in the space exterior to the distributing wall 9, so that such wall and the shell of the retort are at about 1000° 50 or 1100° F. all the time. When the charge of coal within the retort has been coked to the desired extent, steam is introduced through the pipe 35 into the chamber 26 and serves to cool down the coke, so that it 55 will shrink sufficiently to loosen from the walls of the coal tubes. Then the head 3 is released and the weight of the core 24 with the charge of coke carried thereby being sufficient to overcome the counterweights 60 40, the core will drop from the retort, the movement being controlled by brakes or other suitable controlling devices not shown. When the core is sufficiently free from the 65 retort shell 1 the coke gravitates from the core, this being facilitated by the slanting

bottom plate 23. Then the lifting effect of the counterweights 40 is superior to the weight of the core and the latter rises again into the retort, whereupon the bottom head 3 is made fast and the cover 2 having been 70 removed, a fresh charge of coal is introduced. The operation of discharging the coke is sufficient to chill the interior of the retort down to about 700° F., so that the new charge is at first subjected to no greater 75 degree of heat than about 700° F., and is then gradually heated by conduction up to 1000° or 1100° F. in accordance with the heat maintained exterior to the retort. This heating, however, is not uniform throughout 80 each column of coal, but progresses from the outer edge toward the inner edge of each column, at which latter point the gases escape.

85 Experience has demonstrated that certain proportions or sizes are material to the successful operation of the retort. In a commercial form of the retort the shell 1 is nine feet, four inches in length, and the core 24 is seven feet in length. The diameter of the 90 core at the top is twenty-three inches and at the bottom is twenty-seven and three-eighths inches. The walls of the retort are approximately one inch in thickness, while the webs 30 and the wall of the duct 27 are approximately three-fourths of an inch in thickness. The coal tubes 42 in the particular retort referred to have their circumferential width a little less than four inches, or about three and nine-sixteenths, and their radial depth 100 varying from about six inches at the upper end to about eight inches at the lower end. The enveloping wall 9 is about two inches thick and spaced about two inches from the shell 1. With such a retort coking is completed in about three and one-half hours, with some grades of coal, while with other kinds of coal the time of coking is somewhat increased, say, to four or four and one-half hours, but well within commercial limits. 105 Because of the constant removal of the volatilized matter driven off from the coal, the coking proceeds at a temperature harmless to the volatilized matters. The progressive increase of temperature results in a greater 110 yield of oils than heretofore with these oils of a higher grade and the coke produced retains all of the fixed carbon which the coal originally carried.

115 With the retort of the present invention 120 and the treatment of the coal therein to relatively low and progressively increasing temperatures under subatmospheric pressure, and with the bodies of coal sufficiently thin, say, not more than about four inches in 125 thickness, and, furthermore, with the heat so applied as to first affect the coal at one edge and then progressively act through it toward the other edge, at which latter point the gases of distillation are removed, and 130

- also causing the heat to act with progressive intensity along the sides of the body of coal toward the point of exit of the gases, there is obtained a smokeless fuel in the form of coke burning freely with a long flame and containing from five to fourteen per cent. of volatile matter, as desired, while the output of oils condensable from the distillate is materially increased.
13. The amount of volatile matter driven off from the coal varies with the temperature, a larger amount of volatile matter being driven off at the lower temperature employed. For instance, at a temperature of about 700° F. with a certain amount and grade of coal, the volatile matters driven off and condensed may be, say, twenty-three gallons. At 1100° F. with the same quantity and quality of coal but fifteen gallons are obtained. When the temperature is progressively raised from 700° F. to 1100° F. the amount of volatile matters driven off and condensed are in the neighborhood of thirty gallons.
- What is claimed is:—
25. 1. A retort for the destructive distillation of coal having a central duct and a surrounding series of relatively thin chambers with side walls of a material of greater heat conductivity than the coal, each chamber 30 communicating along the inner long edge with the central duct, the retort being arranged for the application of heat thereto at the edges of the coal chambers remote from the central duct and the withdrawal 35 of gases of distillation from the chambers by way of the central duct.
2. A retort for the destructive distillation of coal having a columnar form outer shell, a central duct, and division walls extending 40 from the central duct to the outer shell in spaced relation defining coal chambers of narrow width as compared with their depth, each coal chamber being in constant communication with the central duct along its 45 inner long edge.
3. A retort for the destructive distillation of coal, having a central duct and a surrounding series of longitudinally extended 50 segmental coal receiving chambers, defined by radial webs extending from the central duct to the shell of the retort, each chamber 55 communicating along its long inner edge with the central duct and having its greatest circumferential extent not more than about four inches.
4. A retort for the destructive distillation of coal having a central gas duct and a series of coal receiving chambers surrounding the central duct and communicating 60 therewith along one long side, each chamber being of a size to contain a body of coal not more than about four inches in thickness circumferentially of the central duct.
5. A retort for the destructive distillation 65 of coal comprising an elongated body portion or shell provided with a central longitudinal duct and a surrounding series of chambers exterior to the central duct and extending to the shell of the retort, with the said chambers communicating with the central duct along their inner edges and defining elongated receptacles for coal, each receptacle being of a circumferential width to limit the charge of coal therein to a thin elongated and radially extended layer.
6. A retort for the destructive distillation of coal comprising an elongated body portion or shell provided with a central longitudinal duct and a surrounding series of chambers exterior to the central duct and extending to the shell of the retort, with the said chambers communicating with the central duct along their inner edges and defining elongated receptacles for coal, each receptacle being of a circumferential width to limit the charge of coal therein to a thin elongated and radially extended layer, and a heat distributing wall surrounding the body of the retort in spaced relation thereto.
7. A retort for the destructive distillation of coal comprising a columnar form body portion or shell tapering from the bottom toward the top and provided with removable top and bottom heads, and a core structure within the retort supported by and removable from the core with the lower head, said core structure having a central tubular portion and webs radiating therefrom to the shell of the retort to define coal receiving chambers in surrounding relation to the central tubular portion and communicating therewith.
8. A retort for the destructive distillation of coal having a columnar form body portion or shell, a core comprising a central longitudinal tube with webs radiating therefrom to an extent to substantially reach the shell, and removable heads for the shell with one head sustaining the core and the latter being removable from the shell with said head.
9. A retort for the destructive distillation of coal having a columnar form body portion or shell, a core of less length than the shell and comprising a central tubular duct with webs radiating therefrom and each of a length to reach close to the shell, the central core having perforations between the webs and the core having a bottom plate sloping downwardly and outwardly toward the shell, and said shell having removable heads at the ends with the head at the bottom end sustaining the core and the latter being removable from the retort with said head.
10. A retort for the destructive distillation of coal comprising a columnar form body portion or shell tapering from the bottom toward the top and provided with a core structure having a central tubular por-

tion with webs radiating therefrom to the shell of the retort to define coal receiving chambers in surrounding relation to and communicating with the central tubular portion, said core being removable bodily from the retort.

In testimony, that I claim the foregoing

as my own, I have hereto affixed my signature in the presence of two witnesses.
